UNITED STATES PATENT OFFICE.

EMIL J. CARROLL, OF NORWOOD, OHIO, ASSIGNOR TO THE AMERICAN LAUNDRY MACHINERY COMPANY, OF NORWOOD STATION, OHIO, A CORPORATION OF OHIO.

PADDING.

Application filed June 6, 1924. Serial No. 718,317.

This invention relates to resilient padding for use in ironing or pressing machines.

The object of the invention is to provide improved padding suitable for use on any type of ironing or pressing machine and embodying a supporting metal plate carrying a series of springs, said plate having a smooth lower surface uninterrupted by projections of any kind and hence capable of conforming closely and being fitted exactly to the ironing member. To this supporting plate the springs are connected in a manner to reduce the cost for labor and equipment and simplify the assembling operation and secure a firm, substantial and uniform mounting for said springs which supplies uniform yield throughout the pad and a level upper surface therefor. Moreover, undue flexing or bending of the supporting plate during the ironing operation is avoided.

Further objects of the invention are in part obvious and in part will appear more in detail hereinafter.

In the drawings, Fig. 1 represents a cross section of an ironing roll with the invention applied thereto; Fig. 2 is a sectional elevation of the bed of a garment press provided with my improved padding; Fig. 3 is a plan view of a portion of said bed; Fig. 4 is a detail section showing a spring and associated parts assembled for the securing operation; Fig. 5 illustrates the securing operation; Fig. 6 is a detail section of part of a pad; Fig. 7 is an inverted sectional plan view on the line 7—7, Fig. 6; and Figs. 8 and 9 are respectively a sectional elevation and an inverted plan view illustrating a modification.

The invention may be used in any form of pressing or ironing machine when a resilient pressing or ironing surface is desirable and therefore may be applied either to ironing rolls or to platens or chests with flat, curved or irregular surfaces. In the drawings Fig. 1 shows the invention applied to a hollow heated ironing roll, while Fig. 2 illustrates the hollow heated bed of a pressing machine, upon the upper yielding surface of which the work is supported and pressed or ironed by an upper pressing member (not shown).

The resilient pad forming the present in-

vention comprises a relatively thin metal base plate to which are permanently attached a series of uniformly distributed 55 closely spaced springs of like form, the upper ends of which form the work supporting or engaging surface, separated from the work where desirable only by a relatively thin layer of cover cloth or a suitable layer 60 of woven fabric where additional padding is of advantage. Woven or other asbestos fabric may be used, especially where heat insulating and resisting properties are desirable.

The base plate, indicated at 1, must of course be heavy and strong enough to be durable and not liable to give way under the flexing strains of use and yet be thin enough to enable it to be readily shaped or 70 formed to the curved or other configuration or shape of the pressing bed or the roll to which it is applied. Said base plate has a smooth lower surface characterized particularly by the absence of all projections, such 75 as nuts, screw or bolt heads, rivet heads, spring parts or the like, although it may have any number of through perforations, (not shown) to enable steam, air or other fluid to pass freely through the plate when 80 desired. The smooth bottom surface of the plate enables it to rest directly with full area of contacting surface on the press bed or roll surface and hence in close heat conducting relation therewith, and also enables 85 the plate to be fitted closely to the bed or roll. This is particularly the case in the application of the padding to a roll where the spring carrying base plate may be cut to an exact length according to the circumference 90 of the roll with the certainty that when wound upon the roll, as indicated in Fig. 1, the edges of the plate will meet or abut with an exact or close fit, doing away with all uncertainty in fitting due to irregularity of 95 projections where bolts, rivets or screws are used to fasten the springs or where the springs project through the plate.

For reasons and advantages already stated the springs are therefore suitably assembled with the plate in any manner to leave its lower surface a smooth plane uninterrupted by projections. This conveniently, may be accomplished by a welding

operation, either by spot welding the springs directly to the plate or by securing the springs by some other part which is so welded, or so secured as to produce no bottom plate projections. For example, each spring 2 may have a helical body portion with the upper turn 3 wound in a plane parallel with the plate and having the lower portion of the spring body wound into one, two or more 10 turns of a flat spiral 3^a, also in a plane parallel with the body. A metal disc 4 of less diameter than the inner diameter of the helix is then laid in place over the spiral turns at the spring bottom, said disc preferably being formed with a cupped central depression 5 of such depth as to enter and nearly fill the central spring opening and to nearly if not fully contact with the plate surface. Final securement is effected by 20 introducing into the cup of said disc from above an upper electrode 6 which opposes the lower electrode 7 applied to the lower plate surface. By passing current across the gap between said electrodes the disc and plate are welded together with fairly free 25 flow of the metal to make a continuous integral joint, as at 8, Fig. 6.

With this arrangement each of the springs has a firm substantial foundation, including 30 sufficient turns of the flat spiral so that not only is its securement complete, but it is also more definitely fixed in position than in prior structures where a single relatively small central turn is alone connected to the 35 base plate. The springs, therefore, are not liable to cock and become askew and all of them lie parallel with their axes truly perpendicular to the base plate and with their upper turns all parallel to the base plate 40 and in the same plane. The upper surface of the pad as a whole is therefore more uniform and of a continuity more nearly corresponding to the usual textile paddings. The firm connection of the spring bottom to 45 the base plate not only avoids cocking, but also avoids the continuous application of flexing effects tending to bend the metal of the base plate at each spring and thereby crystallize and break it down. This effect 50 is usually more marked where the padding is applied to a roll which turns in contact with a chest, but the construction described, even in a roll minimizes base plate flexure at 55 the bottom of each spring.

The structure also enables the springs to be more closely spaced relative to each other than in prior arrangements for the purpose, due in some measure to the convenient manner of securing the springs to the plate by 60 the use of simple electrodes, one at the plate bottom and the other entering each spring from the top, and the avoidance of the use of special jigs, tools or dies for securing operations. When the springs are assembled by spot welding, as described they also

may be conveniently spotted at any desired regular or irregular intervals, as determined by the judgment or skill of the operator and the requirement of the particular shape of the chest, bed or roll, and need not be located or spaced in a regular manner, such as is usually necessary when assembled by machines and therefore according to a standard jig or template. 70

Usually the springs are coated or otherwise protected by more or less insulating material, such as enamel or the like, not only for insulating purposes, but also as a rust preventive. Due to the low voltage used in spot welding, the current therefore does not flow appreciably from the disc to the base plate through the spring, but the welding effect is concentrated between disc and plate and the spring turns are unharmed. After securement of the springs to the plate the pad as a whole may be subjected to further operations to reduce or prevent rust or corrosion, such as by dipping it into or spraying it with a rust proof solution such as paint, enamel or the like.

Figs. 8 and 9 show a modification in which the spring is directly secured to the plate by a welding operation, but without a separate disc. Here the bottom of the spring has a part of the wire bent diametrically across its center, as at 10, the wire being raised slightly at its free end or at the spring axis, as at 11, said raised portion being adapted to be engaged by the upper welding electrode and pressed thereby into full welding contact with the plate.

Either of the forms of springs before described may be made of any suitable rust resisting material, such as steel, brass, Monel metal or the like, as will be obvious. 105

What I claim is:—

1. A resilient pad for ironing machines, comprising a metal supporting plate, a series of like springs distributed over the same, and a separate member welded to the plate at each spring and thereby permanently anchoring a portion of each spring to the plate. 110

2. A resilient pad for ironing machines, comprising a metal supporting plate, a series of like springs each having the wire at one end bent into a flat spiral, and a disc welded to the plate at each spring base and with the plate embracing said flat spiral. 115

3. A resilient pad for ironing machines, comprising a metal supporting plate, a series of like springs each having the wire at one end bent into a flat spiral, and a member secured to the plate at each spring base with said member embracing said flat spiral. 120

4. A resilient pad for ironing machines, comprising a metal supporting plate having a smooth lower surface free of projections and perforations, a series of like springs distributed over the upper surface of said plate, and a separate member for permanent- 125

ly anchoring each spring to the plate, said members being secured to the upper surface of said plate.

5. A resilient pad for ironing machines, comprising a metal supporting plate having a smooth lower surface free of projections and perforations, a series of like springs distributed over the upper surface of said

plate, and a separate member for permanently anchoring a portion of each spring to the plate, said members being welded to the upper surface of said plate. 10

In testimony whereof I hereby affix my signature.

EMIL J. CARROLL.
